UNITED STATES PATENT OFFICE

162,367

PERPETUAL CALENDAR

Cecil B. Woofter, St. Paul, Minn., assignor to
Brown & Bigelow, St. Paul, Minn., a corpora-
tion of Minnesota

Application June 30, 1949, Serial No. 3,649

Term of patent 14 years

(Cl. D74—5)

To all whom it may concern:

Be it known that I, Cecil B. Woofter, a citizen of the United States, residing in St. Paul, county of Ramsey, and State of Minnesota, have invented a new, original, and ornamental Design for a Perpetual Calendar, of which the following is a specification, reference being had to the accompanying drawings, forming part thereof:

Figure 1 is a front elevational view of a perpetual calendar showing my new design.

Figure 2 is a rear elevational view thereof.

Figure 3 is an end elevational view thereof.

Figure 4 is a plan view thereof.

The dominant features of my design reside in the specific configuration of the calendar body in combination with the quadrant form, all as shown in the drawing.

I claim:

The ornamental design for a perpetual calendar, as shown and described.

CECIL B. WOOFTER.
